UNITED STATES PATENT OFFICE

GILBERT MICHEL, OF BAGNEUX, FRANCE

METHOD OF MAKING PISTONS

Application filed May 10, 1927, Serial No. 190,316, and in France July 29, 1926.

- Attempts have been made to manufacture pistons by the casting process, using light metals or alloys, in which the piston head or end portion is surrounded by a coating or 5 casing of a strong hard metal, for instance steel, whereby the whole device will be suitably protected and its strength and resistance to wear increased.
- In accordance with the present invention 10 the light metal portion (including the piston head and the lower portion of the skirt) is, for a considerable portion of its length, held within a jacket of a harder and more durable metal, which is less subject to wear, 15 and in the manner of assembling these, the metal of the skirt is pressed into holding recesses in the inner face of the jacket, preferably while both of these are hot, and then the entire device is cooled, leaving the jacket 20 rigidly bound upon the piston body.
- Stated briefly, the invention consists of deforming the roughly forged piston body of light metal (such as magnesium or magnesium alloys) from the interior towards the exterior, upon the interior of a jacket of hard metal, having preferably in the interior face 25 some projections of dovetail shape, the jacket being advantageously initially placed into a matrix.
- It is evident that this manner of procedure 30 permits, on the one hand, a considerable economy in power, since it is the light metal only which is deformed and not the hard metal; and on the other hand, there is obtained a piston needing only a relatively slight exterior shaping and dressing, since the jacket 35 will not have been deformed, especially if it has been held in a proper matrix which conforms to its exterior form.
- The present invention relates particularly 40 to a piston of which the larger portion consists of a light metal or alloy such as magnesium or an alloy of this metal, and the outer body (and optionally the bearing surface of the bosses) of a metal whose mechanical properties are superior to those of most light metals, at the high temperatures to which the pistons are ordinarily subjected 45 when in use.
- The piston head is particularly subject to 50 thermic conditions, and it hence must be given a sufficient thickness. To avoid increasing the weight of this element, the piston head must necessarily consist of very light metals or alloys, such as magnesium and its 55 alloys. On the contrary, the outer body of the piston serves, in use, as a guide and is subjected to considerable friction, and hence must possess great strength and resistance to abrasion when hot, and should therefore 60 preferably consist of a harder metal, for example steel.
- The piston head may advantageously be made of magnesium or a magnesium alloy, and preferably should be subjected to a 65 thermo-mechanical treatment to give the metal a fibrous structure and to improve its thermo-mechanical properties. This treatment may be obtained by forging, die-pressing, stamping, embossing or the like. I prefer to employ the process specified in French Patent No. 607,622, filed on the 7th of March 1925.
- Preferably the whole of the light metal portion, i. e. piston head and skirt, is first 70 cast or otherwise made (i. e. forged or die-cast) from magnesium. This can then be trimmed, e. g. the skirt or a portion of the length of the skirt, may then be turned in a lathe, to give a smooth cylindrical surface. 75 This is then placed within the sleeve, of steel or the like, which entire assemblage is then heated in a matrix. The skirt is then expanded, e. g. by rolling the inside of the same, to force light metal into the dovetails which 80 are located on the interior surface of the sleeve.
- Or, the invention may be carried into effect 85 by separately constructing the said outer body (sleeve) of the piston, of strong metal, provided on its interior face with suitable dovetails and in also constructing a blank for the piston head in magnesium or any alloy of this metal. The outer body is then fitted in the hot state, upon the rest of the piston, with or without preliminary trimming of the latter on its exterior, and the whole device may be completed by the above described outward pressing or like process. 90 This preliminary trimming may consist of 95 100

turning the skirt, to give same a substantially smooth surface.

The appended drawings show by way of example an embodiment of the invention.

5 Fig. 1 represents a half-section taken on the line 1—1 of Fig. 3.

Fig. 2 is a similar half-section on the line 2—2, of Fig. 3.

10 Fig. 3 is a section of the piston on the line 3—3 of Fig. 1.

The said piston comprises a head 1 which may be of magnesium, (preferably forged, die-pressed, etc.).

15 The outer body consists of the strong metal cylinder 3 having on its internal face the dovetails 2 for securing the two parts of the piston together.

20 The said outer body is first placed in the mold or matrix at the proper temperature, and the blank for the cylinder head which consists of magnesium is now hot pressed at a high pressure upon the interior of said outer body, by deformation from the interior to the exterior (viz. outwardly), according to the arrows f^1 and f^2 . In this example, the bearing parts 4 for the wrist pin are formed in the magnesium portion of the skirt.

25 The device must be so arranged that the 30 said outer body will fit tightly upon the main part of the piston.

35 The present invention is not limited to the case in which the light metal of the device has magnesium as a base, and the said metal may be replaced by any other light metal, especially by metals which will assume a fibrous structure when subjected to the mechanical operations as stated above.

40 In the appended claims, the term "metal" 45 includes simple metals and alloys.

I claim:

45 1. Process of manufacturing pistons which comprises placing around a preformed light metal piston, a jacket of hard wear-resisting metal, having recesses upon its interior face, deforming said light metal by pressure from the interior towards the exterior, so that the light metal flows back into said recesses of said jacket, and thus securely joining the jacket to the light metal piston.

50 2. Process of manufacturing pistons which comprises placing around a preformed light metal piston, a jacket of hard wear-resisting metal, having recesses upon its interior face, deforming said light metal by pressure from the interior towards the exterior, so that the light metal flows back into said recesses of said jacket, and thus securely joining the jacket to the light metal piston and allowing 55 the casing to cool upon said light metal core.

60 3. Process according to claim 1, in which the operation of deformation of the light metal by pressure is made at a relatively high temperature, but less than the temperature of 65 softening of the light metal.

4. Process according to claim 1, in which the operation of deformation of the light metal by pressure is carried out while the jacket is in a matrix.

70 5. Process according to claim 1, in which the operation of deformation of the light metal by pressure is carried out while in a heated matrix.

75 In testimony whereof I have affixed my signature.

GILBERT MICHEL.
